[57] CLAIM

The ornamental design for a water control valve, as shown and described.

DESCRIPTION

FIG. 1 is a top plan view of a water control valve showing our new design;

FIG. 2 is a bottom plan view thereof;

FIG. 3 is a side elevational view thereof;

FIG. 4 is an elevational view taken from the side opposite to that shown in FIG. 3;

FIG. 5 is an end elevational view thereof; and

FIG. 6 is an elevational view taken from the end opposite to that shown in FIG. 5.

The broken line showing of hose connectors in FIGS. 1-6 is for purposes of illustration only and forms no part of the claimed design.
